UNITED STATES PATENT OFFICE

148,204

DESIGN FOR A COMBINATION RADIO- PHONOGRAPH CABINET

Herbert L. Weisburgh, New Rochelle, N. Y., as-
signor to Radio & Television, Inc., New York,
N. Y., a corporation of New York

Application July 1, 1946, Serial No. 131,241

Term of patent 3½ years

(Cl. D56—4)

To all whom it may concern:

Be it known that I, Herbert L. Weisburgh, a citizen of the United States of America and resident of the city of New Rochelle, county of Westchester, and State of New York, have invented a new, original, and ornamental Design for a Combination Radio-Phonograph Cabinet, of which the following is a specification, reference being had to the accompanying drawing, forming a part thereof, in which

Fig. 1 is a front perspective view of a combination radio-phonograph cabinet embodying my design with the doors in closed position, and

Fig. 2 is a side perspective view thereof with the doors in open position.

I claim:

The ornamental design for a combination radio-phonograph cabinet, as shown.

HERBERT L. WEISBURGH.
